[57] CLAIM

The ornamental design for a building unit for a space
structure, as shown and described.

DESCRIPTION

FIG. 1 is a top perspective view of a building unit for a
space structure showing my new design;

FIG. 2 is a top plan view thereof; and

FIG. 3 is a bottom plan view thereof; and

FIG. 4 is a left side elevational view thereof, taken
along the line 4—4 of FIG. 3, the right side elevational
view being a mirror image of that shown.

Fig. 1**Fig. 4**

Fig. 2**Fig. 3**
